UNITED STATES PATENT OFFICE.

WILLIAM U. GRIFFITHS, OF PHILADELPHIA, PENNSYLVANIA.

SELF-CLOSING VALVE FOR WATER-CLOSETS.

1,148,836.

Specification of Letters Patent.

Patented Aug. 3, 1915.

Application filed January 26, 1911. Serial No. 604,797.

To all whom it may concern:

Be it known that I, WILLIAM U. GRIFFITHS, a citizen of the United States, residing in the city and county of Philadelphia, 5 State of Pennsylvania, have invented certain new and useful Improvements in Self-Closing Valves for Water-Closets, of which the following is a specification.

My invention relates to improvements in 10 means for automatically closing the valve which controls the flow of water from a source of supply to the flush tank of a water closet apparatus; and also for controlling the opening and closing of a valve which 15 controls the passage through which the waste water is allowed to escape from the pipe which discharges the water into the hopper.

My invention is particularly applicable to 20 water closet apparatus in which the flush tank is allowed to remain empty except at such times as it is desired to flush the water closet hopper.

One of the objects of my invention is to 25 provide a construction of the character named in which automatically operating means for closing the valves as stated may be employed which is positive in action and which may be relied upon at all times to fulfill its purpose and function.

Other objects and advantages of my invention will be set forth hereinafter in the 30 detailed description of my invention or will be apparent therefrom.

In order that my invention may be more 35 readily comprehended and understood, reference may be had to the accompanying drawings in which,—

Figure 1 is a sectional elevation of a water closet apparatus embodying my invention; and Fig. 2 is a section on the line 2—2 40 of Fig. 1.

Referring to the drawings: 1 designates a water closet hopper or basin connected by means of a flush pipe 2 to a flush tank 3.

45 4 designates the water closet seat provided with a rearwardly extending weighted arm 5 the rear end of which is located underneath the lower end of a rod 8 which is supported and guided in bearings 10 upon one 50 side of the flush tank 3. The said rod is bent, as indicated at 11 and 12, and is extended downwardly through bearings 13 to a point in proximity to the bottom of the tank 3.

55 15 designates a valve by means of which the port 16 in the bottom of the flush tank is closed. The valve 15 is preferably sup-

ported upon what may be termed a stem 17 which is pivotally connected to the lower end of the portion of the rod 8 which is located inside of the flush tank 3.

In order to prevent the overflow of the flush tank 3 I have provided an overflow pipe 19 the upper end of which is located a short distance below the upper edge of the tank. Normally, and when not in use, the seat 4 occupies the position shown in Fig. 1 in which it is inclined upwardly from its hinged connection at the rear of the hopper or basin 1 toward the front of said hopper or basin, and is located a short distance above the upper edge thereof,—the distance between the seat and the upper edge of the hopper decreasing from front to rear as shown. When the seat is depressed so that 75 it rests against the upper edge of the hopper or basin 1, the rearwardly projecting arm 5 moves upwardly and lifts the rod 8 to close the valve 15.

A valve controlling rod 20 supported and 80 guided in and by a short bracket 21 is in contact at one end with said seat and at the other end is connected to one end 22 of a lever 23 pivoted at 24 on a bracket 25 extending, in the construction shown, from a 85 valve casing 26. The portion of the said lever 23 upon the opposite side of its pivot 24 extends or passes through an opening 28 in a cam support 29 and at a point beyond said cam support is provided with a weight 30. 90 The valve casing 26 is provided with an opening 31 surrounded by a flange 35 internally screw-threaded to receive a screw-threaded gland 36. Between the inner end of the said gland and the said casing 26 and 95 inside of said flange 35, packing material 37 is provided which surrounds the said cam support 29. The said gland is provided with an opening 38 through which and the opening 31 in the casing the support 29 passes 100 into the valve casing. A wedge-shaped cam 40 on the support 29 is in contact with a valve 41 and is adapted to cause movement thereof to close the water supply pipe 42 and prevent the issuing of water therefrom 105 into the casing 26 and thence through the pipe 43 into the flush tank 3.

In the construction, as illustrated, the cam 40 is moved downwardly in order to close the valve 41 but it will be understood 110 by those skilled in the art that the arrangement may be readily altered so that a movement of the cam in a different direction would cause the same result. When the

cam is moved in the opposite direction, that is, in the constructions shown, when it is raised, the pressure of water from within the pipe 42 against the inside of the valve 41 causes the latter to open to permit the water to flow from the supply pipe. The valve 41, it may be noted, is provided with a stem 44 which is seated and is adapted to slide in the portion of the pipe 42 which is adjacent to the valve. The casing 26 is provided with a port 45 which communicates with a waste pipe 46 having connection with a sewage pipe or conduit (not shown). The cam support 29 is provided with a lateral projection 47 which is integral therewith or otherwise connected thereto, which projection extends between guides 48 upon a side of the casing 26. A washer of rubber or other suitable material 49 on the projection 47 is adapted to be seated over the port 45 and close the same when the cam support 29 is raised by means of the lever 23 or otherwise. In its movement, the support 29 is guided by its bearing consisting of the gland 36 and the sides of the opening 31, the contact of the cam 40 with the valve 41, and the guides 48. By so guiding the support 29 the washer 49 is seated squarely over the port 45 so as to effectively close the same. The base 50 of the casing by means of which the bottom is closed is secured to and is supported upon any suitable support (not shown).

In operation it will be understood that when the seat 4 is depressed the rod 20 is also depressed, causing movement of the lever 23 about its pivot 24 to raise the cam support 29 and permit the pressure of the water from within the water supply pipe 42 to open the valve 41 and permit the issue of water from the pipe 42 into the casing 26 and thence through the pipe 43 into the tank 3. At the same time that the valve 41 is opened the washer 48 moves into position over the port 45 and closes the same. When the seat 4 is permitted to return to the position as illustrated in Fig. 1, the weight 30 causes movement of the lever 23 about its pivot 24 to depress the cam support 29 and cause closure of the valve 41 and at the same time remove the washer 48 from the port 45 to open the pipe 46 and permit the water which is in the pipe 43 and in the upper portion of the casing 26 to escape through the pipe 46 into the sewage pipe or conduit. As the cam 40 moves downward there is a pressure of reaction against the same by the valve 41 so that the end of the projection 47 is wedged or pressed against the side of the valve casing between the guides 48. The valve is thus held securely in position. It is necessary to permit the water to escape from the pipe 43 so as to prevent the freezing of the same therein

and thus insure operation of the apparatus in any and all kinds of weather.

It may be stated that the water closet apparatus is particularly designed for use in outdoor water closets.

The broad subject matter of invention disclosed herein and not claimed is claimed in my co-pending application, filed January 26, 1911, Serial No. 604,795.

Having thus described my invention, I claim:

1. In a device of the character described, the combination of a casing having an inlet port through which water enters the said casing, an outlet port through which water issues from said casing on its way to any desired point, and also a waste water port through which waste water issues from said casing, a valve for opening and closing the inlet port, a valve for opening and closing the waste water port, a support for said waste water valve said support having means for controlling said inlet valve, a pivoted lever having connection with the said valve support, and automatically operating means having connection with the said support for causing movement thereof to cause the opening and closing of said valves.

2. In a device of the character described, the combination of a valve casing having a valve for controlling the supply of liquid thereto and also having a waste water opening leading therefrom, a longitudinally movable rod extending through said casing and having one end projecting therefrom, the said rod having a valve thereon for closing said waste water opening and also having a wedge-shaped cam thereon for controlling the said valve and the said valve casing having means for supporting and guiding the said rod, a lever pivotally supported intermediate its ends and having connection upon one side of its pivot with the projecting end of the said longitudinally movable rod and having a weight secured thereto upon the same side of its pivot for holding the said rod in depressed position, and means for acting upon the portion of the said lever upon the opposite side of its pivot for causing movement of the said rod in opposition to the action of the said weight whereby the said first mentioned valve may be permitted to open and whereby the valve on said rod is moved into position to close said waste water opening.

In testimony that I claim the foregoing as my invention, I have hereunto signed my name this 25th day of January, A. D. 1911.

WILLIAM U. GRIFFITHS.

In the presence of—

GEO. H. WEIDNER,

CARRIE E. KLEINFELDER.
